Primary Examiner — Wan Laymon

(57) **CLAIM**

The ornamental design for a projector bracket, as shown and described.

DESCRIPTION

FIG. 1 is a perspective view of a projector bracket showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the projector bracket where the projector bracket is in a configuration of use;

FIG. 10 is an enlarged view of portion 10 shown in FIG. 1;

FIG. 11 is an enlarged view of portion 11 shown in FIG. 1; and,

FIG. 12 is an enlarged view of portion 12 shown in FIG. 2. The dash-dash broken immediately adjacent to the shaded areas depict the bounds of the claimed design while all other broken lines are directed to environment. The dot-dash broken lines represent boundaries of the enlarged portions and form no part of the claimed design.
